CHARLES NEWTON, OF BUFFALO, NEW YORK, ASSIGNOR OF ONE-HALF TO JOHN F. NAGEL, OF BUFFALO, NEW YORK.

TRIGGER MECHANISM FOR FIREARMS.

1,215,181.

Specification of Letters Patent. Patented Feb. 6, 1917.

Application filed April 22, 1916. Serial No. 92,802.

To all whom it may concern:

Be it known that I, CHARLES NEWTON, a citizen of the United States, residing at Buffalo, in the county of Erie and State of New York, have invented new and useful Improvements in Trigger Mechanisms for Firearms, of which the following is a specification.

This invention relates generally to firearms which are fired from the shoulders or hands and more particularly to firearms having a set trigger mechanism by which the same are discharged.

In firearms of this character as heretofore constructed the full strain of the main spring has usually been exerted against the sear so that it was difficult to obtain a light pull for discharging the firearm, this being due to the fact that the amount of contact which was necessary between the bent of the firing head and the sear to restrain the strength of the main spring precluded an easy release of the firing head bent from the sear. It has also been customary heretofore to employ a double set of triggers viz. a front or releasing trigger, and a rear or set trigger, these triggers being so organized that when the front trigger is pressed the rear trigger flies up and operates a knock-off attached to the sear thus operating the firearm with a much lighter pull than is possible when no set trigger is used. It is frequently desirable to use the front trigger on a direct pull without the intervention of the set trigger and in such cases it is desirable that the front trigger should release the sear from the bent of the firing head and discharge the firearm without undue loss of motion. In all forms of set trigger mechanism heretofore devised it has been necessary to draw the front trigger back a considerable distance before it would engage the knock-off and discharge the firearm by a direct pull.

One of the objects of this invention is to provide a trigger mechanism in which two knock-offs are used and associated in such manner with the front and rear triggers that pressure upon either of the same will release the sear from the bent of the firing head for discharging the firearm and thus enable the same to be operated with a minimum of lost motion.

Another object of this invention is to improve the construction and manner of mounting the front and rear triggers so as

to simplify the same and reduce the cost of manufacture.

A further object of this invention is to provide an improved spring device which is of simple, inexpensive and reliable form and which serves the double function of yieldingly turning both the front and rear triggers so that they tend constantly to move in a direction in which their fingerpieces move forwardly.

In the accompanying drawings: Figure 1 is a fragmentary side elevation, partly in section, of a breech loading firearm equipped with my improvements and showing the trigger mechanism cocked for firing the same with the set trigger knock-off. Fig. 2 is a similar view showing the position of the parts preparatory to cocking the firearm. Fig. 3 is a similar view showing the parts in the position which they occupy after the trigger mechanism is operated so as to fire the gun directly through the releasing trigger knock-off. Fig. 4 is a detached side elevation of the lower frame of the firearm and that part of the trigger mechanism mounted thereon. Fig. 5 is a top plan view of the parts shown in Fig. 4. Fig. 6 is a vertical transverse section taken on line 6-6, Fig. 4. Fig. 7 is a perspective view of the spring for operating the front and rear triggers.

Similar characters of reference indicate corresponding parts throughout the several views.

The main elements of the firearm which are shown in the drawings, as an example of the various forms which are capable of using my improvements, comprise a wooden stock 1, an upper metal frame 2 secured to the upper part of the stock, a lower frame 3 secured to the lower part of the stock, a longitudinally movable firing bolt 4 guided in the upper frame and provided with a firing head 5 having a forwardly facing bent or shoulder 6 on its underside, and a vertically swinging sear 7 arranged in a recess 8 formed in the stock between the upper and lower frames and pivoted at its front end to the upper frame by means of a pin 9. This sear is provided at its rear end with a nose 10 which projects upwardly through an opening 11 in the upper frame in such a position that its rear side may be engaged with the bent of the firing head. The sear is yieldingly held in its operative position in which its nose is arranged in the path of the

firing head bent by means of a spring 12 operating on a forwardly projecting arm 13 of the sear. This spring may operate upon this arm in any suitable manner but as shown in the drawings the same bears at its lower end against the bottom of a socket in the upper side of the arm 13 while its upper end bears against a follower 14 guided in said socket and bearing against a bolt stop 16 or other suitable abutment which may be provided for this purpose.

My improved trigger mechanism which is associated with the above described parts may be variously constructed so far as the details of the same are concerned but in the preferred form of this mechanism that shown in the drawings is suitable and as there shown the same is constructed as follows:

- 20 Direct and indirect knock-offs are arranged transversely side by side in a slot 19 formed lengthwise in the sear and pivotally mounted on the latter by means of a horizontal transverse pin 20 passing 25 through these knock-offs and the adjacent part of the sear. Both of these knock-offs are constructed in the form of cam levers, the front or direct knock-off being provided above and in front of its pivot with a cam or 30 heel 21 and a downwardly projecting front arm 22 while the rear or indirect knock-off is provided above and in rear of its pivot with a cam or heel 23 and a rear arm 25 which projects downwardly and rearwardly.
- 35 17 represents the front or releasing trigger and 18 the rear or set trigger both of which project through a longitudinal slot 27 formed in the lower frame in line with the stock recess and within the trigger 40 guard 28 which projects downwardly from the lower frame. Projecting upwardly from the lower frame along opposite sides of the slot therein and along opposite sides of the central parts of the front and rear 45 triggers are two supporting lugs 29, 29 which are preferably formed integrally with the lower frame. The central part of the front trigger is pivoted to the front parts of these lugs by means of a horizontal 50 transverse pin 31 and the central part of the rear trigger is pivoted to the rear parts of these lugs by means of a horizontal transverse pin 30. The front trigger is provided with a fingerpiece 32 which projects downwardly from the pivoted central part of this trigger into the space within the front part of the guard and above its pivot this trigger is provided with a rearwardly projecting stop lug 33 and an upwardly projecting catch or detent arm 34 which is provided on its rear side with a downwardly facing bent or shoulder 35. On its front side between the upper and lower ends of this trigger the same is provided with a 55 downwardly facing shoulder or seat 36. The

stop lug 33 of the front trigger is adapted to bear against the upper end of an adjusting screw 37 which engages with a screw threaded opening or seat 38 formed partly on opposite longitudinal walls of the slot 27 of the lower frame between the front and rear triggers. By suitably adjusting this screw the forward movement of the fingerpiece of the front trigger and the corresponding rearward movement of its catch 75 arm 34 may be determined.

The rear trigger is provided with a fingerpiece 39 which projects downwardly from the pivoted central part thereof into the space within the rear part of the guard and above its pivot this rear trigger is provided with a forwardly projecting hammer arm 40 which is arranged lengthwise in line with the catch arm of the front trigger. The front end of this hammer arm is so constructed that it may be engaged with the shoulder or bent 35 of the catch arm. The latter is arranged in front of the arm of the front knock-off or cam lever and the hammer arm of the rear trigger is arranged below the arm of the rear knock-off or cam lever.

A spring device is provided which constantly tends to turn the front trigger in the direction for moving its fingerpiece forwardly and its catch arm rearwardly and to move the fingerpiece of the rear trigger forwardly and its hammer arm upwardly. In its preferred form this spring device is constructed of a single piece of spring wire 100 which is bent to form two upper arms 41, 42, two lower arms 43, 44 arranged respectively below the upper arms, two coils 45, 46 each of which connects the rear ends of the companion upper and lower arms forming a pair, an upper horizontal transverse bar 47 connecting the front ends of the upper arms, and a lower horizontal transverse bar 48 projecting laterally from the front end of one of the lower spring arms, the lower spring arm 44 being comparatively short, and the other lower spring arm 43 which carries the lower cross bar 48 being comparatively long and bent downwardly about midway of its length so as to form a 115 downwardly projecting elbow 49 and dividing this long lower spring arm into two front and rear sections which diverge upwardly, as shown in Fig. 7. If desired, the coils 45, 46 may be omitted and the upper and lower arms of the trigger spring connected by plain turns. This spring is mounted so that its arms are arranged lengthwise adjacent to the outer sides of the supporting lugs on the lower frame. The coils of this spring receive opposite ends of the pivot pin 30 which connects the rear trigger with these lugs, the upper cross bar 47 engages with the underside of the hammer arm of the rear trigger, the lower cross bar 48 en- 130

gages with the downwardly facing shoulder 38 of the front trigger adjacent to the front ends of the supporting lugs, the downwardly bent elbow 49 between the front and 5 rear sections of the long spring arm 43 bears against the upper side of the lower frame adjacent to the outer side of one of the supporting lugs and the front end of the short lower spring arm 44 bears against 10 the upper side of the lower frame adjacent to the other supporting lug.

The front parts of the supporting lugs 29 are provided with downwardly facing stop shoulders 50 which are adapted to be 15 engaged by this upper cross bar 47 of the trigger spring and limit the upward movement thereof.

When the firearm is fully cocked preparatory to being fired through the medium of 20 the set trigger by drawing or pulling the fingerpiece of the front or releasing trigger backwardly, the firing head of the bolt is drawn backwardly and engaged with its bent against the nose of the sear, the cams or 25 heels of both knock-off levers are so turned that the same are retracted from the underside of the upper frame, the catch or detent arm of the front trigger is close to the rear side of the arm of the front knock-off lever, 30 and the hammer arm of the rear trigger has been lowered out of engagement from the arm of the rear knock-off lever and engaged with the shoulder of the detent or catch arm, as shown in Fig. 1, in which position 35 of the parts the various parts of the trigger spring are under their maximum tension. Upon now pulling the fingerpiece of the front trigger rearwardly in opposition to the resilience of the trigger spring the first 40 effect is to withdraw the catch shoulder 35 of the front trigger forwardly out of engagement from the hammer arm 40, thereby releasing the latter and permitting the same to be thrown upward by the resilience 45 of the trigger spring engaging therewith. During the first part of this upward movement of the hammer arm the same moves idly from the position shown by full lines in Fig. 1 to the position shown by full lines 50 in Fig. 2, at the end of which movement the hammer arm engages with the underside of the arm of the rear knock-off lever, and during the remainder of the upward movement of this hammer arm the same delivers 55 an upward blow against this knock-off arm during which time this hammer arm and knock-off arm are shifted from the position shown by full lines in Fig. 2 to the position shown by dotted lines in Fig. 2, thereby 60 causing the cam or heel of this rear or indirect knock-off lever, by engaging with the underside of the upper frame, to draw the sear downwardly and disengage its nose from the bent of the firing head, whereby 65 the latter and the bolt are permitted to fly

forwardly under the action of the usual main spring and discharge the firearm. While the firearm is being discharged the upward movement of the upper spring arms 41, 42 and the cross bar 47 connecting the 70 same is limited by engagement of the latter with the shoulders 50 of the lugs 29, as shown in Fig. 4 while the hammer arm 40 continues its movement independently of these parts of the trigger spring and delivers a blow against the rear or indirect 75 knock-off lever. After the firearm has been discharged in this manner the rear knock-off lever rebounds under the action of the sear spring 12 and the set trigger returns to its 80 normal inoperative position, as shown by full lines in Fig. 2, in which the front end of the hammer arm engages with the upper end of the catch arm 22 but does not engage underneath the shoulder of the latter. 85

When the firing head 5 is drawn backwardly and engaged with its bent against the nose of the sear and it is desired to discharge the gun directly by a pull on the front or releasing trigger instead of indirectly through the hammer blow of the rear or set trigger, the trigger mechanism would be arranged in the position shown by full lines in Fig. 2. For discharging the firearm directly while the parts are in this position it is only necessary to pull rearwardly on the fingerpiece of the front or releasing trigger and the result of this operation causes the catch arm of the releasing trigger to move forwardly against the arm 19 of 95 the front knock-off lever and turn the same forwardly, whereby the cam or heel of the latter is caused to operate against the underside of the upper frame and draw the sear downwardly, thereby disengaging the nose 100 of the sear from the bent of the firing head and permitting the firing bolt to fly forward under the action of the main spring and discharge the cartridge. 105

The relative arrangement of the catch 110 arm 34 and the direct or front knock-off lever 22 is such that when the mechanism is set for discharging the gun indirectly through the set trigger and associated parts the rear knock-off lever 25 will be operated 115 to discharge the firearm before the arm 22 of the front knock-off lever has been moved to operate the sear and discharge the firearm, this being preferably accomplished by providing sufficient clearance between the 120 catch arm 34 and the arm 22 of the front knock-off lever for this purpose, as shown in Fig. 1.

By this means the discharge of the firearm may be effected by transmitting the 125 pull on the releasing trigger either directly to the sear or indirectly through the hammer of the set trigger with a minimum loss of motion, thereby increasing the accuracy of the fire and the utility of the firearm ac- 130

cordingly. Furthermore, this trigger mechanism permits of discharging the firearm with a comparatively light pull on the front trigger, thereby reducing to a minimum the liability of interfering with the aim.

This entire trigger mechanism is very simple in construction, the same can be produced at comparatively low cost and the various parts may be assembled or dismembered for inspection or cleaning without requiring any special tool for this purpose.

I claim as my invention:

1. A firearm comprising a movable firing head having a bent, a sear adapted to engage said bent, direct and indirect knock-offs mounted on said sear and engaging a relatively stationary abutment, a releasing trigger engaging with said direct knock-off, and a set trigger engaging said indirect knock-off and controlled by said releasing trigger.

2. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging the operating arm of said direct knock-off, a set trigger having a lower fingerpiece and an upper hammer arm adapted to engage the operating arm of said indirect knock-off and also adapted to be engaged by said catch arm and held thereby in a retracted position, and a spring device for turning said triggers so that their fingerpieces move forwardly.

3. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging the operating arm of said direct knock-off, a set trigger having a lower fingerpiece and an upper hammer arm adapted to engage the operating arm of said indirect knock-off and also adapted to be engaged by said catch arm and held thereby in a retracted position, a spring device for turning said triggers so that their fingerpieces move forwardly and stops for limiting movement of said triggers under the action of said spring device.

4. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engag-

ing the operating arm of said direct knock-off, a set trigger having a lower fingerpiece and an upper hammer arm adapted to engage the operating arm of said indirect knock-off and also adapted to be engaged by said catch arm and held thereby in a retracted position, a frame provided with a slot through which said triggers project and with a supporting lug adjacent to said slot to which the triggers are pivoted, and a spring operating to turn said triggers in the direction in which the fingerpieces of the same move forwardly.

5. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging the operating arm of said direct knock-off, a set trigger having a lower fingerpiece and an upper hammer arm adapted to engage the operating arm of said indirect knock-off and also adapted to be engaged by said catch arm and held thereby in a retracted position, a frame provided with a slot through which said triggers project and with a supporting lug adjacent to said slot to which the triggers are pivoted, and a spring operating to turn said triggers in the direction in which the fingerpieces of the same move forwardly comprising upper and lower spring arms connected at one of their corresponding ends while their opposite ends engage said triggers, respectively.

6. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging the operating arm of said direct knock-off, a set trigger having a lower fingerpiece and an upper hammer arm adapted to engage the operating arm of said indirect knock-off and also adapted to be engaged by said catch arm and held thereby in a retracted position, a frame provided with a slot through which said triggers project and with a supporting lug adjacent to said slot to which the triggers are pivoted, and a spring operating to turn said triggers in the direction in which the fingerpieces of the same move forwardly comprising upper and lower spring arms having one of their adjacent ends connected and mounted on the pivot of said set-trigger, a cross bar arranged on said upper spring arm and engaging said hammer arm, and a cross bar arranged on the free end of said lower arm and engaging with said catch arm, said

lower arm being provided between its ends with a downwardly projecting elbow which rests on said frame.

7. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging the operating arm of said direct knock-off, a set trigger having a lower fingerpiece and an upper hammer arm adapted to engage the operating arm of said indirect knock-off and also adapted to be engaged by said catch arm and held thereby in a retracted position, a frame provided with a slot through which said triggers project and with a supporting lug adjacent to said slot to which the triggers are pivoted, and a spring operating to turn said triggers in the direction in which the fingerpieces of the same move forwardly comprising upper and lower spring arms having one of their adjacent ends connected and mounted on the pivot of said set-trigger, a cross bar arranged on said upper spring arm and engaging said hammer arm, and a cross bar arranged on the free end of said lower arm and engaging with said catch arm, said lower arm being provided between its ends with a downwardly projecting elbow which rests on said frame and a stop arranged on said supporting lug and adapted to be engaged by the cross bar of said upper spring arm.

8. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging the operating arm of said direct knock-off, a set trigger having a lower fingerpiece and an upper hammer arm adapted to engage the operating arm of said indirect knock-off and also adapted to be engaged by said catch arm and held thereby in a retracted position, a frame provided with a slot through which said triggers project and with supporting lugs on opposite sides of

said slot to which the triggers are pivoted, 55 and a spring operating to turn said triggers in the direction in which their fingerpieces move forwardly and comprising a pair of upper and lower arms arranged adjacent to the outer side of each supporting lug and 60 having two of their corresponding ends connected and mounted on the pivot of said set trigger, an upper cross bar connecting the free ends of said upper spring arms and adapted to engage said hammer arm and 65 stops on said supporting lugs, and a cross bar arranged on the free end of one of said lower spring arms and engaging with a shoulder on said releasing trigger, said lower spring arm having the lower cross bar being provided 70 between its ends with a downwardly projecting elbow which rests on said frame.

9. A firearm comprising a movable firing head having a bent, a sear adapted to engage said bent, direct and indirect knock-offs pivoted on said sear and each having a cam engaging with a relatively stationary abutment and having a depending operating arm, a releasing trigger having a lower fingerpiece and an upper catch arm engaging 80 the operating arm of said direct knock-off, a set trigger having a lower fingerpiece and an upper hammer arm adapted to engage the operating arm of said indirect knock-off and also adapted to be engaged by said catch 85 arm and held thereby in a retracted position, a frame provided with a slot through which said triggers project and with supporting lugs on opposite sides of said slot to which the triggers are pivoted, and a spring operating 90 to turn said triggers in the direction in which their fingerpieces move forwardly and comprising a pair of upper and lower arms arranged adjacent to the outer side of each supporting lug and having two of their 95 corresponding ends connected by coils mounted on the pivot of said set trigger, an upper cross bar connecting the free ends of said upper spring arms and adapted to engage said hammer arm and stops on said 100 supporting lugs, and a cross bar arranged on the free end of one of said lower spring arms and engaging with a shoulder on said releasing trigger, said lower spring arm having the lower cross bar being provided between 105 its ends with a downwardly projecting elbow which rests on said frame.

CHARLES NEWTON.
